CHAIR FRAME

Albert F. Staats, San Gabriel, Calif.

Application February 18, 1952, Serial No. 18,553

Term of patent 7 years

(Cl. D15—1)

To all whom it may concern:

Be it known that I, Albert F. Staats, a citizen of the United States and resident of San Gabriel, county of Los Angeles, State of California, have invented a new, original, and ornamental Design for a Chair Frame, of which the following is a specification, reference being had to the accompanying drawing, forming a part hereof, in which:

Fig. 1 is a side elevation of a chair frame showing my new design;

Fig. 2 is a plan view; and

Fig. 3 is a front elevation.

I claim:

The ornamental design for a chair frame, substantially as shown.

ALBERT F. STAATS.
